The ornamental design for a nestable crate with handle, as shown and described.

DESCRIPTION

FIG. 1 is a side elevational view of a nestable crate in accordance with my new design, the opposite side being a mirror image thereof;

FIG. 2 is an end elevational view of the nestable crate of FIG. 1, the opposite side being a mirror image thereof;

FIG. 3 is a top plan view of the nestable crate of FIG. 1;

FIG. 4 is a bottom plan view of the nestable crate of FIG. 1;

FIG. 5 is a cross sectional view of the nestable crate taken along line 5—5 of FIG. 3;

FIG. 6 is a cross sectional view of the nestable crate taken along line 6—6 of FIG. 3;

FIG. 7 is a cross section of the nestable crate taken along line 7—7 of FIG. 3;

FIG. 8 is a cross section of the nestable crate taken along line 8—8 of FIG. 3;

FIG. 9 is a cross section of the nestable crate taken along line 9—9 of FIG. 3;

FIG. 10 is a cross section of the nestable crate taken along line 10—10 of FIG. 4;

FIG. 11 is a cross section of the nestable crate taken along line 11—11 of FIG. 4;

FIG. 12 is an enlarged cross section of the nestable crate taken along line 12—12 of FIG. 4; and,

FIG. 13 is an enlarged fragmented perspective view of a corner area of the crate of FIG. 1.
